UNITED STATES PATENT OFFICE.

TORBJÖRN LINGA, OF THOR, IOWA, ASSIGNOR TO AMERICAN DITCHING MACHINE COMPANY, OF WEST MINNEAPOLIS, MINNESOTA, A CORPORATION OF MINNESOTA.

CATERPILLAR-WHEEL FOR DITCHING-MACHINES.

1,152,525.

Specification of Letters Patent.

Patented Sept. 7, 1915.

Application filed September 30, 1910. Serial No. 584,697.

To all whom it may concern:

Be it known that I, TORBJÖRN LINGA, a subject of the King of Norway, and resident of the city of Thor, county of Humboldt, and State of Iowa, have invented certain new and useful Improvements in Caterpillar-Wheels for Ditching-Machines, of which the following is a full, true, clear, and exact description.

10 My invention relates to heavy ditching machines and has to do particularly with the running gear or wheel members upon which such machines are mounted.

One object of my invention is to provide 15 caterpillar wheels or supporting members for heavy ditching machines, which will present to the ground substantially flat, rigid tread or contact surfaces of comparatively great area and which will in consequence distribute or spread out the weight 20 of the machine over correspondingly large areas of ground surface thereby effectively resisting the tendency of the machine to sink into the ground.

25 Another object of my invention contemplates the provision of caterpillar wheels as above described which will be angularly movable or adjustable independently of each other, but relatively to the machine, which 30 they support in order that they will automatically maintain the whole of their tread surfaces constantly effective regardless of irregularities in the surface of the ground and in order that the machine will travel 35 smoothly.

Another object of my invention is to provide improved caterpillar wheels which will 40 be especially adaptable to ditching machines and the like which are required to operate in soft, yielding or marshy ground, and which will, in proportion to the tread surfaces which they present to the ground, be much lighter in weight than their equivalent in the ordinary type of traction wheels.

45 Further objects of my invention will appear hereinafter.

Reference may be had to the accompanying drawings in which:

Figure 1 is a view in side elevation of a 50 ditching machine, showing one of the caterpillars of my invention in its proper relation to and supporting the rear end of the ditching machine truck; Fig. 2 is an enlarged top plan view of a pair of caterpillar members mounted upon the driving shaft

or rear axle of said ditching machine, one of the caterpillars being shown in section on line 2-2 of Fig. 3; and Fig. 3 is a view in side elevation of the caterpillar wheel:

The caterpillar structure which I have 60 shown in the drawings, and which is representative of my invention, is especially designed for use in supporting the rear end of a ditching machine truck and for the purpose of an understanding of my invention 65 will be described in connection with the ditching machine shown in Fig. 1, although it is to be understood that my invention may be modified to suit the requirements of the particular ditching machine with which it 70 is associated.

The ditching machine shown in Fig. 1 is of the type used for digging narrow trenches or ditches for sewerage or drainage purposes. It comprises a digging element E 75 pivotally supported at the rear end of and adapted to be raised and lowered with respect to its propellable truck T. This truck carries upon it an engine and suitable mechanism for operating the digging element and 80 for transmitting power to and driving the rear caterpillar wheels C to propel the truck along its line of travel. At the rear end of the truck is a transversely disposed axle or driving shaft 28 which is driven through 85 the agency of suitable differential gearing 40 and which extends through sleeve members 35 projecting laterally from the rear end of the truck and carries at its outer ends sprockets 27 for operating the caterpillar 90 wheels to propel the ditching machine along its line of travel.

Referring now more particularly to Figs. 2 and 3: The caterpillar wheel of my invention comprises a frame or transom member 95 which in a sense is in the form of an ellipse the upper and lower portions 4 of which are flattened to form straight lines for a considerable portion of their length and the end portions 5 of which are curved. This transom member is composed of two flat frames or plates 2 and 3 spaced apart and lying in parallel vertical planes, these frames being preferably of cast metal and having openings or cut away portions 6 to 100 render the caterpillars lighter in weight without detracting in the least from their strength or rigidity. The transom so far as the caterpillar member itself is concerned 105 is relatively fixed or stationary, but it has a 110

relative movement with respect to the machine or truck supported by the caterpillars which enables it to assume various angular positions with respect to said machine.

5 Each of the plates or frames 2 and 3 of the transom has a laterally projecting flange 10 adjacent its outer edge, which not only serves as a strengthening rib for the plate but which is grooved on its periphery 10 to form a raceway or runway 12 for the ball or roller bearings 13 upon which runs or travels the relatively movable member or tread belt 14 of the caterpillar. The edges 11 of the frames project beyond the grooved 15 faces of their flanges and prevent the ball bearings from becoming displaced laterally in their raceways. The tread belt or movable member 14 is composed of a plurality of flat, rectangular plates or sections 15 20 transversely arranged and hinged together to form a continuous loop disposed concentrically outside of the transom member and spaced therefrom by the ball bearings 13. These plates or sections may be joined together 25 in any suitable manner to form a broad, flexible belt, but I prefer to connect them by means of a simple hinge joint, each plate being provided with tongues 16 on its longest edges and having holes 30 through which the hinge pins 17 are inserted. The ends of the plates or sections are provided with inwardly directed projections or flanges 31 which together form an almost continuous rib and which maintain the ball bearings 13 from shifting laterally and also strengthen the ends of said 35 plates or sections.

Each plate 15 is provided with two inwardly directed teeth 18 and 19, preferably integrally formed therewith. The teeth 18 are disposed along substantially the longitudinal center of the plate and extend for a considerable portion of the length of the plate. These teeth are preferably 45 arranged in this manner so that they will also serve as strengthening ribs for the plates. The teeth 19 are preferably integrally formed on the central hinge tongue or portion 16 of the plates. Both sets of 50 teeth constitute a continuous series meshing with which is a gear wheel 20 mounted upon a shaft 21 which is suitably journaled in bearings 22 and 23 carried in the curved ends of the frames 2 and 3 respectively of the transom member. This shaft carries on one end outside of the frame 3 a sprocket wheel 25 connected through the medium of a sprocket chain 26 to a similar sprocket driving gear 27 carried on the outer end 55 of the shaft or rear axle 28 of the truck.

A central web 33 is formed in the frames 2 and 3 for the purpose of strengthening the side edges of said frames against bending inward under the weight of the machine. 60 In the upper ends of these webs are bear-

ings 34 in which are journaled the sleeves 35 carried by the rear end of the truck. It is at this point that the caterpillar members are pivotally connected to the truck and is the center about which they revolve bodily 70 to assume various angular positions with respect to the truck so that they will individually adapt themselves to any irregularities in the surface of the ground over which the machine travels. Since the caterpillars are permitted to have this movement with respect to the truck, they will automatically adjust themselves to maintain their areas of tread surface constantly effective to distribute the weight of the truck. 75

The rear axle driving-shaft 28 of the truck is journaled in and projects beyond the ends of the sleeves 35 of the truck, and on these projecting ends the shaft carries the sprocket gears 27 which are connected 85 with the sprockets 25 of the caterpillar driving mechanisms by means of the chain 26. The shaft 25 receives power from the engine carried on the truck through the medium of suitable differential gear mechanism 40 which permits of a relative difference in the speed of the caterpillars when the machine is turning a curve; this being a usual expedient in automobile trucks and the like. 90

It is to be observed that as the tread belt is driven by its mechanism it continually presents to the ground an elongated, flat tread surface which is as wide as the belt itself; that is, in a sense it "crawls" along 100 the ground and at the same time allows the transom member to move progressively forward. When the caterpillar strikes any irregularities in the surface of the ground it automatically swings about its pivotal center with respect to the truck and rides over these irregularities very smoothly. Since the transom member is a rigid, substantial structure it co-operates with the tread belt through the medium of the ball bearings to 110 maintain very rigid that portion of the tread belt which is in contact with the ground. 105

The tread member is movably supported on the transom member through the medium of ball bearings. It will be understood, however, that any other type of bearings, such as roller or disk bearings, may be employed, it being essential, however, that they permit of a relative movement between the tread member and the 115 transom member. It is also desirable that the friction incident to this movement be reduced to a minimum. 120

In the structure which I have shown in the drawings the number of ball bearings 125 in each raceway is greater than twice the number of plates or sections which constitute the continuous tread member; that is to say, each individual plate or section of the tread belt always has at least two points of bearing 130

surface which not only prevents the plate from wobbling or the belt from sagging inward at the joints between its individual sections, but should one of the bearings become crushed or broken the plate will still have one or more additional bearings upon which it is supported.

In the construction which I have shown in the drawings, the pivotal centers about which the caterpillars revolve bodily with respect to the truck are located above substantially the center of the tread surfaces. It is obvious, however, that these pivotal centers do not necessarily have to be directly over the center of the tread surface, that is to say, they may be shifted either way of these centers without detriment to the proper operation of the structure. Further, the power for operating these caterpillars is carried therethrough at a point which is coincidental with the pivotal connection of the caterpillars to the truck. In this manner the driving mechanism is in constant operative relation to the caterpillars regardless of any position to which they angularly adjust themselves.

While I have shown and described one embodiment of my invention herein, I wish it to be understood that my invention is capable of considerable modification without departing from the spirit thereof.

I claim:

1. In a traction machine having a live axle, an elongated caterpillar traction element carried thereon and comprising a horizontally elongated frame member pivotally mounted adjacent its middle portion and above the center thereof on said axle, a traction belt encircling the frame movable thereon and composed of a series of metallic plates hinged together, a central row of inwardly projecting teeth on said belt, a transverse shaft rotatably mounted in the rear end of said elongated frame, a gear wheel on said shaft adapted to engage the teeth on the belt to drive same, and driving means connecting said transverse shaft and the axle for transmitting power from the axle to said belt.

2. In a traction machine having a live axle, an elongated caterpillar traction element carried thereon and comprising a horizontally elongated frame member pivotally

mounted adjacent its middle portion and above the center thereof on said axle, a traction belt encircling the frame movable thereon and composed of a series of metallic plates hinged together, a central row of inwardly projecting teeth on said belt, a transverse shaft rotatably mounted in one end of said elongated frame, a gear wheel on said shaft adapted to engage the teeth on the belt to drive same, and driving means connecting said transverse shaft and the axle for transmitting power from the axle to said belt.

3. In a traction machine having a live axle, an elongated caterpillar traction element carried thereon and comprising a horizontally elongated frame member pivotally mounted adjacent its middle portion and above the center thereof on said axle, a traction belt encircling the frame movable thereon, and composed of a series of metallic plates hinged together, a row of inwardly projecting teeth on said belt, a transverse shaft rotatably mounted in the rear end of said elongated frame, a gear wheel on said shaft adapted to engage the teeth on the belt to drive same, and driving means connecting said transverse shaft and the axle for transmitting power from the axle to said belt.

4. In a traction machine having a live axle, an elongated caterpillar traction element carried thereon and comprising a horizontally elongated frame member pivotally mounted adjacent its middle portion and above the center thereof on said axle, a traction belt encircling the frame movable thereon and composed of a series of metallic plates hinged together, a row of inwardly projecting teeth on said belt, a transverse shaft rotatably mounted in one end of said elongated frame, a gear wheel on said shaft adapted to engage the teeth on the belt to drive same, and driving means connecting said transverse shaft and the axle for transmitting power from the axle to said belt.

In testimony whereof, I have hereunto set my hand, this 10th day of September, 1910, in the presence of two subscribing witnesses.

TORBJÖRN LINGA.
